UNITED STATES PATENT OFFICE

154,989

DESIGN FOR A PLASTIC CLOTHESPIN

Lester P. Clark, Milltown, N. J.

Application August 24, 1948, Serial No. 148,276

Term of patent 14 years

(Cl. D17—6)

To all whom it may concern:

Be it known that I, Lester P. Clark, a citizen of the United States of America, residing at Milltown, in the county of Middlesex and State of New Jersey, have invented a new, original, and ornamental Design for a Plastic Clothespin, of which the following is a specification, reference being had to the accompanying drawing, forming a part thereof, wherein:

Figure 1 is a view in side elevation of a plastic clothespin, showing my new design.

Figure 2 is an edge view, and

Figure 3 is a plan view.

I claim:

The ornamental design for a plastic clothespin, as shown.

LESTER P. CLARK.
